Patented Mar. 30, 1976

239,360

SRETCHER BAR

Jules Kliot, 2150 Stuart St.,
Berkeley, Calif. 94705

Filed June 11, 1973, Ser. No. 368,932

Term of patent 14 years

Int. Cl. D8—05

U.S. CL. D8—15

FIG. 1

FIG. 2

FIG. 3

FIG. 4

FIG. 1 is an isometric view of a stretcher bar showing my new design;

FIG. 2 is a horizontal section view thereof taken on line 2—2 of FIG. 4, and shown broken away for ease of illustration;

FIG. 3 is a side elevation view thereof shown broken away for ease of illustration; and

FIG. 4 is a right side elevation view thereof.

I claim:

The ornamental design for a stretcher bar, substantially as shown and described.
